US00D561084S

(12) **United States Design Patent** (10) Patent No.: **US D561,084 S**
(45) Date of Patent: **** Feb. 5, 2008**

(54) **HELICOPTER PROPELLER**

(75) Inventor: **Chi Pok Billy Wai**, Quarry Bay (HK)

(73) Assignee: **Silverlit Toys Manufactory, Ltd.**,
Hong Kong (HK)

(**) Term: **14 Years**

(21) Appl. No.: **29/281,955**

(22) Filed: **Jul. 6, 2007**

Related U.S. Application Data

(63) Continuation of application No. 11/627,919, filed on Jan. 26, 2007, which is a continuation-in-part of application No. 11/465,781, filed on Aug. 18, 2006, which is a continuation-in-part of application No. 11/462,177, filed on Aug. 3, 2006, application No. 29/281,955, which is a continuation-in-part of application No. 29/275,322, filed on Dec. 20, 2006, now Pat. No. Des. 546,269, and a continuation-in-part of application No. 29/275,323, filed on Dec. 20, 2006, now Pat. No. Des. 544,825, and a continuation-in-part of application No. 29/275,324, filed on Dec. 20, 2006, now Pat. No. Des. 545,755, and a continuation-in-part of application No. 29/277,652, filed on Mar. 5, 2007, now Pat. No. Des. 552,531, and a continuation-in-part of application No. 29/280,187, filed on May 18, 2007, now Pat. No. Des. 554,040.

(57) **CLAIM**

The ornamental design for a helicopter propeller, as shown and described.

DESCRIPTION

FIG. 1 is a left side view of a helicopter propeller, showing my new design;

FIG. 2 is a left side perspective view thereof;

FIG. 3 is a right side view thereof;

FIG. 4 is a right side perspective view thereof; and,

FIG. 5 is a top view thereof.

Broken lines, if any, are for illustrative purposes only and form no part of the claimed design.
